LAMP BASE

Eugene R. Davis, 139 Denver Blvd.,
San Antonio, Tex. 78210

Filed Feb. 27, 1968, Ser. No. 10,741

Term of patent 14 years

U.S. Cl. D48—20
Int. Cl. D26—02

FIG. 1

FIGURE 1 is a plan view of a "Lamp Base" embodying my new design, the opposite sides of the cross and the plaque being flat and unornamented. FIGURE 2 is a side view thereof. FIGURE 3 is a bottom view thereof.

The dominant features of my design reside in the portions shown in full lines.

I claim:

The ornamental design for a lamp base, as shown and described.
